UNITED STATES PATENT OFFICE.

SILVESTER F. WILSON, OF FRUITVALE, CALIFORNIA.

FASTENER.

1,253,658.

Specification of Letters Patent. Patented Jan. 15, 1918.

Application filed October 27, 1916. Serial No. 128,081.

To all whom it may concern:

Be it known that I, SILVESTER F. WILSON, a citizen of the United States, residing at Fruitvale, in the county of Alameda and State of California, have invented certain new and useful Improvements in Fasteners, of which the following is a specification.

The present invention has reference generally to fasteners and more particularly relates to a fastener especially adapted for use on shoes.

As a primary object the present invention contemplates the provision of a flexible shoe fastener capable of expanding and contracting over the instep with the movement of the foot to consequently obviate the employment of shoe laces which have a tendency to prevent circulation of blood in the foot of the wearer, thus providing for the comfort of the wearer of the shoe.

It is an equally important object of the present invention to provide novel resilient means which have associated therewith novel engaging means for engagement with the upper of the shoe from that to which the resilient means is connected.

As an additional improvement the invention embraces the provision of a novel buckle to which is connected the resilient means, the buckle being removably mounted and having the form of a cam lever whereby when engaged and swung to a closed position, the resilient means will be maintained in an operative position across the instep of the shoe.

A more specific feature of the present invention consists in the provision of a hook for receiving the buckle and capable of movement when the buckle is swung into a closed position to facilitate the operation of the latter.

Among the other aims and objects of the present invention may be recited the provision of a device of the character described with a view to compactness, and in which the number of parts are few, the construction simple, the cost of production low and the efficiency high.

Other objects as well as the nature, characteristic features and scope of my invention will be more readily apparent from the following description taken in connection with the accompanying drawings, and pointed out in the claims, forming a part of this specification.

The invention is clearly illustrated in the accompanying drawings, in which:

Figure 1 is a perspective, showing the invention applied to a shoe,

Fig. 2 is an enlarged transverse section taken on the line 2-2,

Fig. 3 is an enlarged front elevation of one of the fasteners,

Fig. 4 is an enlarged transverse sectional detail of one form of spring,

Fig. 5 is an enlarged transverse section of another form of spring.

Similar characters of reference are employed in all of the above described views to indicate corresponding parts.

Referring now, more particularly to the accompanying drawings, I have illustrated a shoe 1 including the uppers 2 and 3 and a tongue 4. At the outset, it is to be understood that the specific construction of the shoe forms no important part of this invention which resides principally in the fastener and which is capable of use in various connections, however, it will likewise be understood that it is desirable to use the fastener on a shoe.

In the present instance, each of the fasteners consists of an attaching plate 5 fastened by means of suitable rivets 6 to the inner surface of the upper 2. Coil springs 7 of a type such as is illustrated in Figs. 4 and 5 are now provided. A pair of springs 7 have their outer ends 8 connected in suitable openings 9 adjacent the ends of the attaching plate 5, while they pass through suitable openings in the upper 2 and have their opposite ends connected in clips 10 which are in turn pivotally associated with my improved buckle 11. In this instance, the buckle is preferably formed from a single piece of wire which is bent into triangular form to provide a body 12, the base of which is pivotally associated with the clips 10, while the intermediate portion of the base is offset in substantially U-form to provide a hook 13 while directly opposite on the vertex is formed a finger-loop 14. A receiving hook 15 is connected to the upper 3 by means of a suitable rivet 16, the hook 15 being adapted to receive the hook 13 of the buckle.

The operation of the invention is as follows:

Assuming that the fasteners are applied to the shoe 1 and it is desired to fasten them so that they will assume the position illus-

trated in Fig. 1, the finger portion 14 of each buckle is engaged and moved against the tension of the springs 7 so as to arrange the hook 13 in the hook 15. The intermediate portion of this hook 15 now serves as a pivot, while the bend in the hook 13 acts as a cam so that in effect the buckle serves as a cam-lever of the second class, since the springs serve as the weight, while the point of application of power is on the loops 14. As the buckle is swung about its pivot and pressed against the upper 3, the hook 15 is moved away from the upper 3 so that the tension of the springs on the buckle will be arranged off center and thus maintain the buckles in position.

If desired, the buckles may be protected by leather covers 17. These will render the fasteners more pleasing to the eye, when used on a shoe and it is thought that the advantages of the invention when in use will be readily apparent when the device is used on a shoe. As indicated, the springs expand and contract with the movement of the foot and do not interfere with the circulation, consequently making the shoes easy on the feet of the wearer.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described and all statements of the scope of the invention, which as a matter of language, might be said to fall therebetween.

Having thus fully described my invention, what I claim and desire to secure by Letters Patent is:

1. A fastener comprising resilient means adapted to be connected to one end of an article to be fastened, a receiving hook carried by the other end of the article, and an engaging loop connected to the resilient

means and detachably engageable with the receiving hook, said loop being adapted to be rotated in the receiving hook which serves as a pivot against the tension of the resilient means so that the loop is positioned to maintain the fastener in a closed position. 55

2. A shoe fastener including an attaching plate and adapted to be pivotally connected to one of the uppers of a shoe, a pair of springs connected to the plate, hook-like engaging members loosely connected to the springs, and a receiving hook secured to the other upper for receiving the member and serving as a pivot on which the member is 60 65 swung to removably hold the uppers together when the hook is engaged by said member.

3. A fastener comprising a pivotally mounted yoke plate adapted to be attached 70 to the end of an article to be fastened, a plurality of resilient elements each having one end secured to the yoke and carrying a clip at the other end, a substantially triangularly shaped detachable member having one side 75 approximately U-shaped to form a hook with spaced bearing portions, said clips being loosely connected to the member on the bearings, and a stationary hook member attached to the other end of the article and 80 adapted to be engaged by the hook of the detachable member.

4. A shoe fastener including an attaching plate adapted to be secured to one of the uppers of a shoe, a coil spring connected to 85 the attaching plate, clips carried by the ends of the spring, a hook-like member rotatably associated with the clips, a receiving hook carried by the other upper for receiving the hook portion of the member and 90 to serve as a pivot therefor when the member is engaged with the receiving hook to vary the tension of the spring as the member is rotated off center maintaining the fastener in closed position. 95

In testimony whereof I affix my signature in presence of two witnesses.

SILVESTER F. WILSON.
